MEANS FOR COOLING THE LUBRICATING
OIL IN INTERNAL COMBUSTION ENGINESJames L. Barnes, Winslow, Ariz., assignor of one-
half to Theodore G. Grieder, Winslow, Ariz.

Application October 23, 1935, Serial No. 46,405

3 Claims. (Cl. 123—196)

This invention relates to improvements in means for cooling the lubricating oil of an internal combustion engine, and contemplates the use of a refrigerant for this purpose.

- 5 The principal object of this invention is to provide means for dissipating the heat of the oil in the crank case, oil reservoir, or oil line of an internal combustion engine thereby maintaining the proper viscosity of the oil.
- 10 A further object of the invention is to produce a device of this character which may be used in the ordinary engine without materially altering its construction.

15 A further object is to produce a device of this character which is economical to manufacture, install and operate.

Other objects and advantages will be apparent during the course of the following description.

20 In the accompanying drawings forming a part of this specification and in which like numerals are employed to designate like parts throughout the same,

25 Fig. 1 is a side elevation of an engine having my invention applied thereto;

Fig. 2 is an end elevation of my invention showing outline of a crank case in broken lines;

Fig. 3 is an enlarged top plan view looking into the crank case of the engine;

Fig. 4 is a side elevation of Fig. 3;

30 Fig. 5 is a bottom plan view of the cooling plate;

Fig. 6 is a side elevation of a manifold;

Fig. 7 is an end elevation of the unit in assembling position, and

35 Fig. 8 is a bottom plan view of the cooling tubes.

In the accompanying drawings wherein for the purpose of illustration is shown a preferred embodiment of my invention, the numeral 5

40 designates the engine as a whole having an oil sump 6 in the bottom of the crank case. It is in this oil sump that I place one or more cooling units, which units consist of a hollow cooling pan

45 7 having a curved upper surface 8 and a flat bottom surface 9. The bottom surface is drilled so as to provide openings 11 of any desired number. These openings are on opposite sides of the pan and are connected together by curved copper tubes 12. Each of these tubes are connected by a manifold 13, see Figs. 4 and 7.

In Fig. 1 I have shown a pipe 16 leading from the condenser and expansion valve or liquid receiver to the manifold 13, which refrigerant then

passes through pipes 12 into pan 7 and is withdrawn through the top of pan through pipe 14 to the compressor and thence to the condenser 17 to complete the cycle. It is obvious that any type of refrigerant may be employed which will 5 perform the desired function.

It is apparent that a unit of this type would require very little power and that by properly cooling the oil its viscosity would remain sufficiently heavy to prevent the oil leaking past the 10 piston rings and thus saving in oil consumption. In hot climates the oil often becomes very thin and due to the excessive heat of the engine this thin oil burns and does not properly lubricate. It is to avoid such difficulties that I have devised 15 my invention.

It is to be understood that the form of my invention herewith shown and described is to be taken as a preferred example of the same and that various changes relative to the material, 20 size, shape, and arrangement of parts and various changes relative to the location or placement of the cooling units may be resorted to without departing from the spirit of the invention or the scope of the subjoined claims. 25

Having thus described my invention, I claim:—

1. An oil cooler for an internal combustion engine comprising a cooling pan having a curved upper surface, a flat lower surface, said lower 30 surface having orifices being connected by curved pipes and a manifold connecting said curved pipes.

2. An oil cooler for an internal combustion engine comprising a cooling pan having a curved 35 upper surface and a flat lower surface, said pan being hollow, a plurality of pipes connected to the bottom of said pan, and a manifold connecting said pipes, means for delivering a cooling medium to said manifold thence through 40 said pipes into said pan to be withdrawn through an opening in the top of said pan.

3. A cooler for oil in an internal combustion engine including a hollow pan, a plurality of depending pipes each having its opposite ends 45 connected to said pan and adjacent its opposite longitudinal margins, and a manifold connecting the medial portion of each of said pipes whereby fluid entering said manifold may pass into and through said pipes thence into said pan 50 to be withdrawn through an opening in the top of said pan.

JAMES L. BARNES.
